H. M. CARROLL, SR

DENTURE

Filed Nov. 13, 1922

H. M. Carroll, Sr. Inventor

By *C. A. Snow & Co.*
Attorney

UNITED STATES PATENT OFFICE.

HOUSTON MUNROE CARROLL, SR., OF SAN ANTONIO, TEXAS.

DENTURE.

Application filed November 13, 1922. Serial No. 600,590.

To all whom it may concern:

Be it known that I, HOUSTON M. CARROLL, Sr., a citizen of the United States residing at San Antonio, in the county of Bexar and 5 State of Texas, have invented a new and useful Denture, of which the following is a specification.

This invention aims to provide a novel retainer for a lower plate of teeth, the retainer being so constructed that it will present a grinding surface, and serve as a tooth, as well as a retainer.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown 25 can be made without departing from the spirit of the invention.

In the accompanying drawings:—

Figure 1 shows in top plan, a device constructed in accordance with the invention; 30 Figure 2 is a fragmental side elevation; Figure 3 is a cross section; and Figure 4 is a plan disclosing the lower surface of the combined retainer and tooth.

In the drawings, the numeral 1 marks a plate or carrier, of arched form, and made of gutta-percha or any other substance ordinarily used in dental work, the lower surface of the plate 1 being shaped, as at 2 in the common and well known way, to provide the necessary seat for the plate. Teeth 3 are mounted on the plate 1. Any suitable means may be provided for attaching to the plate, the combined retainer and tooth which forms the subject matter of this 45 application. If the retainer and tooth is to be applied to a set of teeth already made, it may be expedient to cut away the plate or carrier 1, at its rear end, and on its upper surface, as shown at 4 to receive a layer 5 of material which, generally, is the same out of which the plate 1 is made. The layer 5 of material extends horizontally, as at 6, across the upper surface of the carrier 1 at the rear end thereof, and extends downwardly along the side of the plate or car-

rier 1, at the outside thereof, as denoted by the numeral 7.

A combined retainer and tooth 8 is provided, and has a grinding surface 9. The retainer and tooth 8 includes an upstanding, 60 outwardly extended projection 10, beneath which the part 7 of the layer 6 extends, in order to sustain the retainer and tooth, the lower surface of the member 8 being roughened, as indicated at 11 to secure a firm hold 65 in the part 6 of the layer 5, whilst the same is in a plastic condition.

The element 8 exercises a double function, in that it causes the rearmost tooth on the plate to act as a retainer. The part 70 8 is easy to adjust on any plate which is worn, a portion of the back part of the plate being removed, as hereinbefore explained, and the combined retainer and tooth being mounted in place, the full grinding surface 75 of the set being retained and, in some instances, an increased grinding surface being secured, since the element may be placed further back than is the ordinary artificial tooth. The involuntary contractions 80 of the muscles of the mouth in the act of masticating food, cooperate with the retainer, and aid in holding the plate in place. The retainer 8 may be made of any suitable substance which can be worn without injury 85 to the health of the patient, gold, aluminum or porcelain being suggested.

Having thus described the invention, what is claimed is:—

1. In a device of the class described, a lower set of artificial teeth provided at its rear end with a laterally prolonged retainer having a grinding surface.
2. In a device of the class described, a lower set of artificial teeth comprising a plate; a combined retainer and tooth co-acting with the rear portion of the plate and having a grinding surface, the retainer and tooth including a laterally projecting part; and means for securing the retainer and tooth to the plate, said means being extended beneath said part.

In testimony that I claim the foregoing as my own, I have hereto affixed my signature in the presence of two witnesses.

HOUSTON MUNROE CARROLL, Sr.
